United States Patent Office

Des. 192,290
Patented Feb. 27, 1962

192,290

LOUDSPEAKER

Denis Eads Johnson, Chicago, and Joseph Palma, Jr.,
Wheaton, Ill., assignors to The Muter Company (Jen-
sen Manufacturing Company Division), Chicago, Ill.,
a corporation of Illinois

Filed July 6, 1961, Ser. No. 65,853

Term of patent 14 years

(Cl. D26—14)

Fig. 3.

Fig. 4.

FIG. 1 is a perspective view of a loudspeaker showing our new design;

FIG. 2 is a perspective view showing the rear portion of the loudspeaker;

FIG. 3 is a side elevational view; and

FIG. 4 is a rear elevational view.

The essential features of the design reside in the portions shown in solid lines of the drawing.

We claim:

The ornamental design for a loudspeaker, substantially as shown and described.
